UNITED STATES PATENT OFFICE.

JAMES HOUGH, OF GUELPH, ONTARIO, CANADA.

BOTTLE-OPENER.

No. 926,807.

Specification of Letters Patent.

Patented July 6, 1909.

Application filed March 2, 1908. Serial No. 418,839.

To all whom it may concern:

Be it known that I, JAMES HOUGH, of the city of Guelph, in the county of Wellington, in the Province of Ontario, Canada, have invented certain new and useful Improvements in Bottle-Openers, of which the following is the specification.

My invention relates to improvements in bottle openers, and the object of the present invention is to provide a construction for moving the closure cap or crown of a bottle and it consists essentially of a device having flat spicular projections extending inwardly from the side bars thereof and between the bar supporting the corkscrew and the end bar, such projections being designed to be inserted underneath the edge of a crown cap when the corkscrew is raised, whereby the opposite end of the device may be utilized to form the device into a lever, so that the projections may with facility raise the crown or cap as hereinafter more particularly explained.

Figure 1, is a plan view of a device provided with my improvement. Fig. 2, is a sectional view.

In the drawings like letters of reference indicate corresponding parts in each figure.

A is the opener, which comprises the side bars A¹, end bar A² and cross bar A³, which carries a corkscrew A⁴.

A are flat spicular projections located at the back of the device and extending inwardly from the side bars thereof of which 35 they form part.

The projections are opposite each other and may be of any suitable form and are located between the bar on which the corkscrew is held and the end bar.

The device may be manipulated to remove 40 a crown cap by throwing the corkscrew upwardly and placing the end bar of the device on top of the cap and the projections A⁶ beneath the edge of the cap, when by raising the opposite end the crown cap may be re- 45 moved.

What I claim as my invention is:

1. A bottle opener comprising a U-shaped member, a cross bar connecting the free ends of the parallel portions of the U together, a 50 corkscrew on said cross bar, and a flat inwardly projecting portion A⁶ on each leg portion of the U intermediate the ends thereof.

2. A bottle opener comprising a member having parallel leg portions, and a bar connecting one end of one portion to the corresponding end of the other portion, a bar connecting said parallel portions intermediate their ends, and a flat inwardly projecting portion having a pointed end on each parallel portion intermediate the two connecting bars, the pointed ends of said flat portions extending toward the end connecting bar. 55 60

JAMES HOUGH.
